UNITED STATES PATENT OFFICE

2,514,885

SECTIONAL JEWELRY

Virginia A. Mazurk, New York, N. Y.

Application March 4, 1947, Serial No. 732,229

2 Claims. (Cl. 63—3)

1

This invention relates to improvements in jewelry articles and, more specifically, to sectional jewelry and to a new and improved linking system for sectional jewelry such as bracelets, necklaces, and the like.

One object of the present invention is the provision of a device of the character described which affords a sturdy, reliable, and durable linkage for ornamental chains and for all types of sectional jewelry.

Another object of the present invention is the provision of a device of the character described which reduces the assembly cost and facilitates the manufacture of sectional jewelry.

Still another object of the present invention is the provision of a device of the character described which is of a highly attractive appearance, light in weight, and comparatively simple in construction.

With the foregoing and other objects in view which will appear as the description proceeds, the invention consists of certain novel details of construction and combination of parts hereinafter more fully described and pointed out in the claims, it being understood that changes may be made in the construction and arrangements of the parts without departing from the spirit of the invention as claimed.

In the accompanying drawing the preferred form of the invention has been shown.

In said drawing

Figure 1 is a fractional plan view of a preferred embodiment of my invention;

Figure 2 is a side elevation of the same; and

Figure 3 is a cross-sectional view on the line 3—3 of Fig. 1.

Similar reference characters refer to similar parts throughout the several views.

In the drawing the numeral 1 denotes a setting for a gem or for an ornamental plate 2. According to the present invention, each piece of sectional jewelry consists of a plurality of settings 1 which are connected to one another by means of links 3 in the manner described hereinafter.

Each setting 1 comprises a pair of frame members 4 and 5 which have ledges 6 and 7 that are rectangular, as in the instance shown, or of any other suitable shape or design and adapted to encompass an ornamental plate 2 of glass or the like or a gem, when the members 4 and 5 are placed one upon the other with their ledges 6 and 7 adjacent each other, as may be seen in Figs. 2 and 3.

The upper narrow sides 8 and the lower narrow sides 9 of the members 4 and 5 are preferably

2

straight, as in the instance shown, and a pair of studs 10, which are semi-circular in cross-section, are extended from each side 8 and from each side 9. The outer end portions 11 of the studs 10 are preferably semi-spherical, and the studs 10 are located at the edges of the ledges 6 and 7, so that they form cylindrical portions when the members 4 and 5 are placed one upon the other in the manner previously referred to and illustrated in the drawing.

The narrow sides 12 and 14 of the frame members 4 and 5 are preferably provided with ornaments 15, and the front sides 16 are preferably provided with ornamental perforations 17, through which the plates 2 or the like are visible.

The members 4 and 5 are held together by means of rings 18, which preferably are resilient split rings, engaging the studs 10 and being interposed thereon between the semi-spherical head portions 11 and the links 3.

The links 3 can be any suitable linking members. However, I prefer to make them as oblong members each of which consists of two parallel, straight portions 30 which are connected to each other by circular, outwardly bulging sections 31.

When assembling a plurality of settings 1 and link members 3, so as to form a chain or the like, the straight portions 30 of the link member 3 are bent outwardly, so that the pintle portions 10 and 11 can be inserted therebetween; then the portions 10 and 11 are shifted toward the end sections 31, and the latter are pressed around the pintle portions 10 and 11 in order to obtain the form of the link members 3 as shown in Fig. 2. In this way the distance between the portions 30 is smaller than the diameter of a pair of adjacent studs 10, so that the latter cannot get out of place but will always be kept in spaced relation to the studs 10 of the next following setting 1, due to the fact that the sections 31 partially encircle the studs 10.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having thus fully described my said invention,

what I claim as new and desire to secure by Letters Patent in the United States is:

1. A piece of sectional jewelry comprising a plurality of settings each of which consists of a pair of frame members adapted to hold a gem therebetween and having two parallel narrow outer sides from each of which extends a pair of studs which are semi-circular in cross-section and which have semi-spherical thickened extremities, link members connecting the studs of adjoining settings to one another, and a resilient split ring interposed between the semi-spherical extremities of each adjacent pair of studs and a link member, all substantially as described.

2. A piece of sectional jewelry comprising a plurality of settings each of which consists of a pair of frame members having rectangular ledges on opposite sides and being provided at opposite narrow sides with studs which are semi-circular

in cross-section and which have semi-spherical extremities, a split ring engaging each adjacent pair of said studs for holding each pair of said frame members together so that their ledges form a chamber encompassing a plate placed between two frame members, and link members connecting said studs of the settings to one another, said split rings being interposed between said link members and the semi-spherical extremities of said studs, all substantially as described.

VIRGINIA A. MAZURK.
